UNITED STATES PATENT OFFICE.

EDWARD M. BENTLEY, OF WASHINGTON, DISTRICT OF COLUMBIA.

ELECTRIC WAY.

SPECIFICATION forming part of Letters Patent No. 276,954, dated May 1, 1883.

Application filed March 27, 1883. (No model.)

To all whom it may concern:

Be it known that I, EDWARD M. BENTLEY, a citizen of the United States, residing at Washington, in the District of Columbia, have 5 invented certain new and useful improvements in electric cables and their application to an anti-inductive system of electric ways, of which the following is a specification.

My invention consists in a specific arrangement of the direct and return wires of a double electric circuit, so that they shall be everywhere practically equidistant from any disturbing circuit, and in their combination into a system to be used in the vicinity of disturbing wires. It is fully illustrated in the accompanying drawings, wherein—

Figures 1, 2, 3, and 4 represent cables embodying my invention. Fig. 5 represents a core made up of several parallel wires. Fig. 20 6 represents a diagram of the manner of their use in a system.

C represents the core of the cable, which may be simply a rope or rod of insulating material, as in Figs. 3 and 4, or may be composed 25 of an insulated wire, as shown in Fig. 1, or several wires, as shown in Figs. 2 and 5. Around C, Fig. 1, are wound in substantially parallel helices the direct and return wires D and R of an electric circuit, they being insulated in any manner, either before being wound 30 on the core or by being embedded in the material of the core itself. It will be seen that D and R, being thus wound, have always the same relative position to any external wire as 35 A, and neither affect it inductively nor are affected by it. It will also be seen that they are similarly situated with respect to an internal wire, T, so that the core can be made up of such wires, and they will all be inductively independent of the wires D and R. In 40 Fig. 1, D and R represent a telegraph-circuit, and T a telephone-wire; but this arrangement may be reversed, as shown in Fig. 2, or any other electrical translating devices used on the 45 various circuits. Where C is made up of insulated wires they may be a simple bundle of straight parallel wires, as shown in Fig. 5; or a number of wires, T, may be wound on a core, c, and the whole then serve as a core upon 50 which wires D and R may be wound. This arrangement is illustrated in Fig. 2.

As thus far described, the invention provides for but one direct and return circuit in a cable. Any number of direct and any number of return circuits may, however, be used. In 55 Fig. 3 are shown four direct circuits, each provided with a battery, transmitter, and receiver, and one common return circuit therefore, two direct being on each side of the common return. In Fig. 4 there are six direct and 60 two return circuits. Any number of wires may be used as direct circuits and any number as return circuits. For telegraphic purposes, where the quantity of electricity to be carried is small, and on long lines, where the 65 common return is only run a short distance, as to the edge of the city or outside the area of inductive disturbance, one common return can be used for a number of direct circuits. It can be used with a still greater number if the batteries on one half of the direct circuits have 70 their positive and the other half their negative plates connected to the common return, as shown in Fig. 3. I do not claim this arrangement of batteries.

In the diagram Fig. 6, D and R represent, respectively, the direct and common return circuits for trunk lines starting from the central office, O, and running along the main street of a city and off to a distant station. 80 D' and R' represent the direct and common return circuits used for local business and starting from the same central office. It is to be understood that they are all running in the vicinity of other disturbing wires, more especially in the manner set forth in a pending application of even date herewith filed by myself as joint inventor with Walter H. Knight. The common return R of the through lines is grounded outside the city limits or the area of 85 inductive disturbance of light and telephone wires. Its resistance compared with the total length of the through-line wires is therefore very small, although it may be small in cross-section, and the effect will be the same 90 as if all the through lines were grounded at the central office. The local lines are not grounded at all, but all return through the common wire R'. L is a loop of a local line 95 passing through the stations a, b, c, and d, and as at each point of the loop there is a direct wire accompanied by its corresponding return 100

wire, it is anti-inductive to any line in its vicinity. L' is a second loop going through stations e, f , and g . This loop is anti-inductive only from h to r , a single circuit going completely around the block J . M and N are sub-stations connected with the central office by several wires, which are in each case accompanied by the common return.

The advantage of this system is that by the addition of a small number of wires for returns existing systems can be rendered inductively independent of other wires wherever it is necessary, no change in or addition to the present instruments being required. As no telegraph-wires are grounded in the city, there will be no danger of telephone-wires being disturbed by branch currents from ground-plates, which is considered one of the most prolific sources of telephone disturbance.

I hereby reserve the right to claim more completely the system and other matters herein shown or described, but not claimed, in subsequent applications.

What I claim as my invention is—

1. The combination of the direct and return limbs of an electric circuit, wound on a conducting-core made up of one or more single limbs of an electric circuit.

2. The combination of several direct conductors and one or more common return conductors therefor, each direct conductor and the common return conductor or conductors

being practically equidistant from any neighboring parallel conductor.

3. The combination of several direct conductors, forming distinct circuits, and a common return therefor, the whole arranged in anti-inductive relation to neighboring parallel circuits.

4. The combination of several direct conductors and one or more return conductors therefor, the whole arranged in anti-inductive relation to neighboring parallel circuits, the return conductors being arranged symmetrically between the direct conductors.

5. The combination of several direct conductors and a common return therefor with neighboring disturbing wires, the return conductor being grounded outside the area of inductive disturbance.

6. The combination of several direct conductors, forming portions of independent circuits, and a common return therefor, with loop-circuits taken from the direct conductors, as described.

7. The combination of several direct conductors and a common return therefor of a branch from the common return, serving as a return for one or more of the direct conductors.

EDWARD M. BENTLEY.
